UNITED STATES PATENT OFFICE

1,991,778

TOOL

James Arnold Taylor, Tyler, Tex.

Application May 21, 1934, Serial No. 726,848

1 Claim. (Cl. 254—28)

This invention relates to a tool designed primarily for use in pulling staples used in securing wire fencing to its supporting posts.

An important object of the invention is to provide a tool of this character wherein the jaws are so constructed that they will pass readily within a staple when the handles of the tool are brought together, whereby a slight turning of the tool will result in the staple being extracted.

Another object of the invention is to provide a tool including inwardly curved jaws circular in cross section and tapered to fine points, one jaw being longer than the adjacent jaw whereby the long jaw will pass under the cooperating jaw, creating a wedging action under the staple, to prize the staple from its position, in such a way that the staple and wire held thereby, will not be damaged by the tool.

A still further object of the invention is to construct the jaws in such a way that the wedging action of the jaws will be increased as the jaws are moved towards each other.

With the foregoing and other objects in view, which will appear as the description proceeds, the invention resides in the combination and arrangement of parts and in the details of construction hereinafter described and claimed, it being understood that changes in the precise embodiment of the invention herein disclosed may be made within the scope of what is claimed, without departing from the spirit of the invention.

Referring to the drawing:

Figure 1 is an elevational view of a staple pulling tool constructed in accordance with the invention.

Figure 2 is a side elevational view of the tool showing the jaws in their open positions.

Figure 3 is a sectional view taken on line 3—3 of Figure 1.

Figure 4 is a sectional view taken on line 4—4 of Figure 3.

Figure 5 is an enlarged detail view illustrating the cut away portions at the free ends of the jaws.

Figure 6 is an elevational view illustrating the wire cutting blades of the jaws, with a wire positioned therebetween.

Referring to the drawing in detail, the tool comprises a pair of pivotally connected members

5 and 6, the pivotally connected members embodying handles 7 and jaws 8.

These jaws 8 are circular in cross section and taper towards their free ends, one of the jaws being curved in a greater arc of a circle than its 5 cooperating jaw, so that the free ends of the jaws overlap each other, when the handles are brought together in the act of extracting a staple.

One of the jaws has its upper surface slightly cut away as at 11, the opposite jaw having its 10 lower surface cut away at 12 so that the jaws may overlap when they are brought together.

It might be further stated that the construction of these jaws is such that as the free ends of the jaws move over each other when a staple 15 is being extracted, a wedging action takes place to the end that when the jaws have been moved to the limits of their inward movements, the staple which is being extracted, has been moved to such a position that by a slight movement of 20 the tool, the staple is easily removed.

Adjacent to the pivot points of the jaws, are blades 9, which blades are inclined, providing wire cutting means, the inclined construction causing the wire under treatment to be forced 25 towards the pivot point of the members 5 and 6, eliminating any possibility of the wire passing from between the blades, during the cutting operation.

The members 5 and 6 are also provided with 30 teeth 10, which cooperate in providing pliers when the handles are moved inwardly towards each other, to the end that the tool may be readily employed in twisting or pulling wire.

Having thus described the invention, what is 35 claimed is:

Staple removing pliers comprising pivotally connecting members, embodying jaws and handles, said jaws being curved in the arc of a circle and tapered to fine pointed ends, the outer surface of one of the jaws adjacent to the pointed end thereof, being cut away, the inner surface of the opposite jaw, adjacent to the pointed end thereof, being cut away, whereby the pointed end of one jaw may move into the cut away portion 45 of the adjacent jaw when the jaws are brought together, and said jaws adapted to move under a staple to wedge the staple from its position within a supporting post.

JAMES ARNOLD TAYLOR. 50
